UNITED STATES PATENT OFFICE.

ROBERT B. WOLF AND HARRY E. TIDMARSH, OF SANDY HILL, NEW YORK.

PAPER-MAKING MACHINERY.

No. 878,849.

Specification of Letters Patent.

Patented Feb. 11, 1908.

Application filed July 14, 1906. Serial No. 326,209.

To all whom it may concern:

Be it known that we, ROBERT B. WOLF and HARRY E. TIDMARSH, both citizens of the United States, both residing at Sandy 5 Hill, county of Washington, State of New York, have invented certain new and useful Improvements in Paper-Making Machinery; and we do hereby declare the following to be a full, clear, and exact description of the invention, such as will enable others skilled in the art to which it appertains to make and use the same.

The invention relates to paper making machines, it having more particular reference to that type of machines known as pulp presses, wet machines and the like.

The particular object in view is to provide an extremely simple and efficient means for preventing leakage of stock from the stock 20 vat to the white-water receptacle along the sleeve or sleeves, with which the cylinder mold or screen is provided and through which the water, drawn through the cylinder mold or screen, passes to the white-water 25 receptacle.

In the accompanying drawing, which illustrates the application of the invention to the stock vat and cylinder mold of a wet machine, the single figure represents a longitudinal sectional view of the stock vat, showing the cylinder mold in elevation.

In the particular embodiment of the invention illustrated in the drawing, *a* represents the stock vat of a standard wet machine, which is adapted to receive the ground wood pulp, sulfite pulp or paper pulp, admixed with large quantities of water and to deliver the pulp, largely freed from water, to the "felt", not shown, which runs in contact 35 with the surface of the cylinder mold *b*, and thence over the ordinary couch-roll, as will be readily understood by those skilled in the art. It is desired to have the white-water, which passes through the wire cloth, with 40 which the cylinder mold is covered, free from pulp or paper fibers, as large quantities of it cannot be used again, and the fibers it holds in suspension are in consequence lost.

In Letters Patent of the United States No. 50 838,167, granted us under date of August 7, 1906, we have set forth a very effective way in which leakage from the stock vat to the white-water receptacle or chamber may be prevented, the same consisting of an intermediate chamber located between the stock vat and the white-water chamber or recep-

tacle which effectively traps any leakage or seepage, from either the stock vat or the white-water chamber and prevents any admixture of the materials contained in the vat 60 and chamber.

In the present invention, the essential object in view is also to obviate this leakage, but without the necessity of providing an intermediate chamber between the stock vat 65 and the white-water receptacle. To accomplish this result, there is provided an annular flange or collar formed on the sleeve or sleeves of the cylinder mold, the same serving to prevent leakage from the stock vat 70 following the sleeve further than the flange or collar, the leakage or seepage being thrown off or directed by the flange or collar into a suitable spout or receptacle located beneath the said annular flange. In order to reduce 75 as much as possible this leakage from the stock vat along the sleeve to the annular flange or collar, suitable packing means is provided between the end walls of the vat and the sleeves of the cylinder mold, through 80 which the white-water is discharged from the interior of the cylinder mold to the white-water receptacle.

The stock vat *a* is preferably of rectangular form, and of sufficient size to receive the 85 cylinder mold *b*, which is adapted to deliver into suitable spouts *c*, one at each end of the vat, the white-water drawn through the meshes of the screen surface of the cylinder mold, said white-water passing from said 90 cylinder mold by way of the hollow axial sleeves *d*. These spouts *c* are so constructed as to partially encompass the sleeves in order to prevent any loss of material, and the spouts have suitable connections leading to 95 the chambers or receptacles which are used for collecting and holding the white-water delivered to the spouts from the cylinder mold by way of the axial sleeves *d*. Each of the sleeves *d*, at the point where it joins the 100 head of the cylinder mold, is provided with an off-set shoulder *e*, between which and the collars *f*, (which in the present invention constitute the end walls of the stock vat), is an annular packing ring *g*, which may, if de- 105 sired, be made up of a series of sections to completely fill the space between said shoulders and said walls and in a large measure prevent leakage of stock from vat *a* past the shoulder *e* and along the sleeve *d*. In order 110 to insure a still more effective sealing of the joint between the end of the cylinder mold

and the end wall of the vat, there is provided a packing sleeve *h* of felt which encircles and gages the peripheral edges of the packing ring *g* and the shoulder *e*.

Upon each of the sleeves, between the end walls of the stock vat *a* and each of the spouts *c*, is formed an annular flange or collar *i* preferably made integral therewith, although not necessarily so, said flange or collar serving to throw off from said sleeve any leakage or seepage which might work its way along the sleeve from the stock vat. In order to catch the drippings or leakage from the flange or collar, and also to collect any of the leakage past the shoulder *e*, packing sleeve *h* and packing ring *g*, which does not follow along the axial sleeves, there is provided a spout *j*, as shown, which may be connected by means of a suitable pipe to a stock chest or other receptacle from which the pulp may be again delivered to the stock vat *a*. This spout is located adjacent the end walls of the vat and directly beneath the annular flange *i*, and it is also to be noted that the same is similar in construction to the white-water spout *c*, in that it partially encompasses the sleeve at this point in order to prevent any loss of the stock.

Reference has been made to the collars *f, f*, as constituting the end walls of the stock vat *a*. These collars *f, f* are each divided along a horizontal line and provided with a circular opening to embrace the sleeve *d*, the two sections of each collar being fastened together around the sleeve so that the collars may be removed and inserted with the cylinder mold. Each of the collars are held against suitable guides or cleats *k* by any desirable fastening means, so that when the cylinder is in place, leakage past the edge of the collars is prevented.

As will be readily understood, the cylinder mold is built around the usual rotating shaft *l*, which is supported in suitable bearings *m* formed upon the standards or supports *n* located a suitable distance from the ends of the stock vat.

It will be apparent from the above description, that the apparatus used is very efficient, and one that will absolutely prevent any leakage of stock from the stock vat into the spout *c*, which leads to the receptacle used for holding the white-water, except, however, such small quantities as might pass through the wire cloth of the cylinder mold, for the reason that any of the stock which might leak past the joint between the shoulder *e*, the packing sleeve *h* and the packing ring *g*, and follow along the sleeve *d*, will be thrown off from the sleeve, or conducted, by the annular flange or collar *i*, into the spout *j* and carried back into the stock vat or some other stock chest provided for that purpose.

It will also be apparent that, while the invention has been shown and described as

applied to both ends of the stock vat and cylinder mold, it is nevertheless true that it may be desired to blank off one end of the mold, thereby dispensing with the arrangement of sleeve, packing rings, and the spouts *c* and *j* at that end, and applying the invention to the other end of the apparatus only. Furthermore, it will be understood that the details of construction and the relative arrangement of parts may be varied, without departing from the spirit and scope of the invention, as for example, instead of the particular packing means to prevent leakage from the stock vat along the cylinder sleeves, packing glands or stuffing boxes of the ordinary kind may be employed. Also instead of providing the spouts *c* and their connections leading to the white-water receptacles, the white-water receptacles could be built around the ends of the sleeves and adapted to receive the white-water, by way of the sleeves from the cylinder mold, directly therefrom.

What we claim is:—

1. The combination of a stock vat, a cylinder mold having an axial sleeve, a white-water receptacle in communication with the interior of the cylinder mold by way of said sleeve, a spout or receptacle for collecting the leakage from said vat, and means for directing any leakage which follows along the sleeve into said spout or receptacle.

2. The combination of a stock vat, a cylinder mold having an axial sleeve, a white-water receptacle in communication with the interior of the cylinder mold by way of said sleeve, and means on said sleeve for preventing the leakage from said vat following the sleeve past said means.

3. The combination of a stock vat, a cylinder mold having an axial sleeve, a white-water receptacle communicating with the interior of the cylinder mold by way of said sleeve, means on said sleeve for preventing leakage between said vat and white-water receptacle, and packing between the wall of the stock vat and the sleeve.

4. The combination of a stock vat, a cylinder mold therein having an axial sleeve and a shoulder between the sleeve and the cylinder end, a white-water receptacle in communication with the interior of the cylinder mold by way of said sleeve, means on said sleeve for preventing leakage between the stock vat and said white-water receptacle, and a packing collar or washer surrounding said sleeve and engaging the wall of the stock vat and the shoulder of the cylinder respectively.

5. The combination of a stock vat, a cylinder mold therein having an axial sleeve and a shoulder between the sleeve and the cylinder end, a white-water receptacle communicating with the interior of the cylinder mold by way of said sleeve, means on said

- sleeve for preventing leakage between the stock vat and said white-water receptacle, a packing collar or washer surrounding said sleeve and engaging the wall of the stock vat
5 and the shoulder of the cylinder respectively, and a packing sleeve engaging the packing collar and shoulder of the cylinder respectively and overlying the joint between the two.
- 10 6. The combination of a stock vat, a cylinder mold therein having an axial sleeve, a white-water receptacle communicating with the interior of the cylinder mold by way of said sleeve, and an annular flange or collar
15 on said sleeve for preventing the leakage from said vat following the sleeve past said flange or collar.
7. The combination of a stock vat, a cylinder mold therein having an axial sleeve, a
20 white-water receptacle in communication with the interior of the cylinder mold by way of said sleeve, an annular flange or collar on said sleeve for preventing the leakage from
- said stock vat following the sleeve past said flange or collar, and a spout or receptacle for collecting the said leakage. 25
8. The combination of a stock vat, a cylinder mold therein having an axial sleeve, a white-water receptacle in communication with the interior of the cylinder mold by way of said sleeve, a spout or receptacle for collecting the leakage from said vat, an annular flange or collar on said sleeve for directing the leakage along the sleeve from the stock vat into the spout or receptacle, and a connection between the spout and a stock chest or other storage receptacle for discharging the collected leakage from the stock vat. 30
- In testimony whereof we affix our signatures, in presence of two witnesses.
